UNITED STATES PATENT OFFICE.

FRANK DE COLIGNY, OF CHICAGO, ILLINOIS.

POWER-TRANSMITTER.

No. 870,814.

Specification of Letters Patent.

Patented Nov. 12, 1907.

Application filed April 24, 1907. Serial No. 369,961.

To all whom it may concern:

Be it known that I, FRANK DE COLIGNY, a citizen of the United States, residing at Chicago, in the county of Cook and State of Illinois, have invented a new and useful Improvement in Power-Transmitters, of which the following is a specification.

My invention relates to an improvement in the class of power transmitters, in which the driving and driven wheels form, between them, intercommunicating chambers for oil serving as the power-transmitting medium between abutments on the respective wheels for transmitting the rotary motion of one to the other.

The primary object of my invention is to provide a novel and simple construction of power-transmitter involving the principle of operation referred to.

In the accompanying drawings, Figure 1 is a broken view showing my improved transmitter in sectional elevation, the section being taken at the irregular line 1-1 on Fig. 2 and viewed in the direction of the arrows; and Fig. 2 is a section taken at the line 2 of Fig. 1 and viewed in the direction of the arrow, showing the transmitting mechanism mainly in elevation, with the separable side of the outer wheel removed.

On the drive-shaft 3 is mounted, to rotate with it, a hollow drive-wheel 4 consisting of a side 5 having a sleeve 6 and a central hub 7 alining with the sleeve, a rim 8, and a side 9 screwed to the rim and provided with a hub 10 and a sleeve 11 extending therefrom and containing a stuffing-box 12. Surrounding the sleeve 11, and adapted to rotate therewith, is the longitudinally shiftable sleeve 13, serving the purpose hereinafter explained. A driven-shaft 14 is journaled in the hub 7, wherein it is surrounded by a bearing 15, preferably of Babbitt metal, and extends loosely through the hub 10 and through the stuffing-box in the sleeve 11. On the shaft 14, is secured at its hub 16 to rotate with the shaft, a wheel 17 having a web 18 and a peripheral rim 19 fitting closely between the sides of the drive-wheel, with which it is concentric. Within the wheel 4, between the rims 8 and 19, is an annular partition 20 fitting between and let into the sides of the drive-wheel, to which it is securely fastened by screws 21. The annular partition divides the space between the driving and driven wheels into an outer chamber 22 and an inner chamber 23, this partition extending circumferentially from a point 24 to a point 25, between which points it forms the opening 26 to afford open communication between the two chambers for the circulation of the liquid, preferably oil operating in the manner hereinafter described. Adjacent to the opening 26 is formed in the partition 20 a port 27 flanked by guide-recesses 28, 28 extending transversely of the partition for reciprocably confining guide-flanges 29, 29, extending from a slide valve 30, adapted to regulate the extent of opening and closing the port 27. A stem 31 extends from the valve 30 through a stuffing-

box 32 in the wheel-side 9, beyond which its outer end is connected with the adjacent end of a lever 33 provided on its opposite end with a yoke 34 straddling and pivotally connected at 35 with the sleeve 13, and fulcrumed between its ends on a bearing 36 projecting from the head 9.

For shifting the sleeve 13 to move the valve 30, an operating lever 37 is provided, suitably fulcrumed at 38 on a stationary bearing 39 and connected with the sleeve in a manner to permit rotation thereof. The connection shown consists of a yoke 40 straddling a circumferential groove 41 formed about the outer end of the sleeve 13, and a fork 42 in which the lever 37 terminates, straddling the yoke 40 and connected at its lower ends therewith by pivot-pins 43.

At the opening 26 is pivotally supported at one end in the adjacent end 24 of the partition 20, an abutment 44, containing a passage 44', the abutment fitting snugly but movably between the inner surfaces of the sides of the drive-wheel and yieldingly held at its free end in contact with the rim 19 of the driven-wheel, by a spring 45 fastened to the adjacent guide-bearing for the valve 30. At diametrically opposite points in the wheel 17 are formed, through its rim 19 and extending into the web 18, the recesses 46, 47. In the recess 46 is pivoted at one end an abutment 48, to work at its free end against a metal wearing plate 49, let into the recess, in which is secured a spring 50 for yieldingly holding the abutment in bearing contact at its free end with the inner surface of the partition 20; the abutment fitting endwise snugly but movably between the wheel-sides 5 and 9. A similar abutment 51 is pivotally supported in the same way in the recess 47, and is pressed by a spring 52; this recess being also equipped with a wearing plate 53 for the free end of the abutment.

To the opposite inner surfaces of the sides 5 and 9 of the drive-wheel are fastened to extend between the points 54 and 55 in the chamber 23 similar crescent-shaped cam-plates 56, 56, for the purpose hereinafter explained; and for a purpose supplementing that of these cams, the rim 19 of the driven-wheel has provided upon it, adjacent to the free ends of the abutments 48 and 51, the similar cam-surfaces 57, 58.

The operation is as follows: With the chambers 22 and 23 filled with oil, as the preferred liquid for the purpose, and which is free to flow in both chambers through the passage 44' in the abutment 44, and with the parts in the relative positions illustrated except that the valve 30 is completely closed, rotation of the wheel 4 in the direction indicated by the arrow at 59 in Fig. 2, will rotate the wheel 17 in the same direction, indicated by the arrow 60, and at the same speed since the oil confined between the abutments 44 and 48 cannot escape and forms an unyielding power-transmitting medium between them. Opening the valve, more or less, by manipulating the lever 37 to shift the sleeve 13

and thereby turn the lever 33 on its fulcrum, permits a proportionate quantity of the oil between the abutments 44 and 48 to escape into the chamber 22, with the result that, in the continued rotation of the drive-wheel 5 at the same speed, the abutment 44 travels with more or less lost motion, thereby riding the cams 56 upon the abutment 48 and forcing it inward. Thus a space is produced between the cams and the edge of the abutment contacting therewith, through which the oil ahead 10 of the abutment 44 may pass. In this way the speed of the driven-wheel is reduced relative to that of the driving-wheel. As will be understood, until the cams 56 have ridden over the abutment 48 sufficiently far to force it entirely into its recess 46, that abutment, and 15 the abutment 51 will oppose the abutment 44; while the abutment 51 will alone oppose the abutment 44 when the abutment 48 is wholly within its recess. Inasmuch as neither abutment 48 or 51 enters its respective recess far enough to avoid obstructing the abutment 44 when 20 it meets the same, the cam surfaces 57, 58 are provided to ride the abutment 44 over them. It will furthermore be understood that maintaining the valve open to any given extent, maintains the same relative reduction of speed of the driven wheel, while the relatively greater 25 speed of rotation of the driving wheel causes the cams to act necessarily on the abutments 48 and 51 in the manner described; and that the greater the extent to which the valve is opened, the greater will be the extent of reduction in the speed of the driven wheel, because of the increased outflow of oil from between the 30 co-operating abutments.

What I claim as new and desire to secure by Letters Patent, is—

1. In a power-transmitter of the character described, 35 the combination of a hollow drive-wheel on its shaft, a driven-wheel on its shaft supported within said drive-wheel, a partition forming intercommunicating oil-chambers between said wheels and containing a valved port, means for operating the valve of said port, a spring- 40 pressed abutment supported to contact with the rim of said driven-wheel, spring-pressed abutments supported on the driven-wheel to contact with said partition, and cams in the inner chamber, into the path of which said abutments on the driven-wheel extend, for the purpose set forth.

2. In a power-transmitter of the character described, 45 the combination of a hollow drive-wheel on its shaft, a driven wheel on its shaft supported within said drive-wheel, an annular partition forming intercommunicating oil-chambers between said wheels and containing a valved port, means for operating the valve of said port, a spring- 50 pressed abutment containing a passage and supported in the communication between said chambers to contact with the rim of said driven-wheel, spring-pressed abutments 55 supported on the driven wheel to contact with said partition, and cams in the inner chamber, into the path of

which said abutments on the driven wheel extend, for the purpose set forth.

3. In a power-transmitter of the character described, 60 the combination of a hollow drive-wheel on its shaft, a driven-wheel on its shaft supported within said drive-wheel, a partition forming intercommunicating oil-chambers between said wheels and containing a valved port, means for operating the valve of said port, a spring-pressed abutment supported to contact with the rim of 65 said driven-wheel; spring-pressed abutments supported on the driven-wheel to contact with said partition, cams in the inner chamber, into the path of which the abutments on the driven-wheel extend, and cams on the driven-wheel in the path of said first-named abutment, for the purpose 70 set forth.

4. In a power-transmitter of the character described, 75 the combination of a hollow drive-wheel on its shaft, a driven-wheel on its shaft supported within said drive-wheel, an annular partition forming intercommunicating oil-chambers between said wheels and containing a port, a slide-valve supported in guides at the sides of said port and provided with a stem extending through the drive-wheel, lever-mechanism connected with said valve for operating it, a spring-pressed abutment supported to contact 80 with the rim of said driven-wheel, spring-pressed abutments supported on the driven-wheel to contact with said partition, and cams in the inner chamber, into the path of which said abutments on the driven-wheel extend, for the purpose set forth. 85

5. In a power-transmitter of the character described, 90 the combination of a hollow drive-wheel on its shaft, a driven-wheel on its shaft supported within said drive-wheel, an annular partition forming intercommunicating oil-chambers between said wheels and containing a port, a slide-valve supported in guides at the sides of said port and provided with a stem extending through the drive-wheel, a sleeve on the driven-shaft longitudinally movable thereon, a lever fulcrumed between its ends and connected at its opposite ends respectively with said stem and sleeve, 95 and an operating-lever having a yoke-connection with said sleeve for shifting it, a spring-pressed abutment supported to contact with the rim of said driven-wheel, spring-pressed abutments supported on the driven-wheel to contact with said partitions, and cams in the inner chamber, 100 into the path of which said abutments on the driven-wheel extend, for the purpose set forth.

6. In a power-transmitter of the character described, 105 the combination of a hollow drive-wheel on its shaft, a driven-wheel on its shaft supported within said drive-wheel and having a rim contacting with the sides thereof, spring-pressed abutments pivotally supported in recesses in said driven-wheel, an annular partition in said drive-wheel forming therein an inner and an outer chamber and containing an opening and a valved port, an abutment 110 pivoted supported in said opening and containing a passage through which said chambers intercommunicate, cams in said inner chamber for engaging said abutments, and means for operating said valve, for the purpose set forth.
